STARTING MECHANISM FOR AUTOMOBILES.

1,215,453.

Specification of Letters Patent. Patented Feb. 13, 1917.

Application filed January 5, 1915. Serial No. 587.

To all whom it may concern:

Be it known that I, CHARLES E. WILSON, a citizen of the United States, and a resident of Wilkinsburg, in the county of Allegheny and State of Pennsylvania, have invented a new and useful Improvement in Starting Mechanism for Automobiles, of which the following is a specification.

My invention relates to starting mechanisms for automobiles, and particularly to means for controlling the operative connection of starting motors to the shafts of internal-combustion engines.

My invention has for its object to provide a simple arrangement whereby a starting motor may be automatically connected to, and disconnected from, the shaft of an internal-combustion engine.

My invention comprises the combination of a motor having a longitudinally shiftable armature with a screw threaded shaft which operates to shift a pinion into and out of mesh with a coacting gear wheel, according as the motor constitutes the driving or the driven member.

Motors having normally-displaced armatures for controlling the connections above described have heretofore been employed, but it has been necessary, in such constructions, to employ complicated switching mechanisms and resistors to prevent rotation of the armatures until the coacting gear wheels are placed in mesh. This arrangement is necessary because, in the displaced position of the armature, the torque is sufficiently high to rotate the armature at a comparatively high rate of speed before the gear wheels are in operative position.

Starting mechanisms embodying screw-threaded shafts for shifting the pinion into and out of mesh with the usual fly-wheel gear possesses the disadvantage of shifting the pinion toward the fly wheel with great force. It is necessary to provide a resilient connection between the shaft and the pinion because of the impact with which they are brought together and their rigid relation which prevents any relative movement in case the teeth do not register properly.

According to the present invention, the pinion on the motor shaft is shifted longitudinally both by the movement of the displaced armature as it is returned to its central position and by the action of the screw-threaded shaft as it rotates relatively to the

pinion. By means of this construction, the pinion is shifted through the greater part of its path of movement before the armature shaft has reached a relatively high speed, and the impact above mentioned is thereby avoided. In case the coacting teeth are not in position to mesh readily, the slideable mounting of the armature shaft permits rotation of the pinion relatively to the fly-wheel gear and the parts may be readily meshed.

The details of my invention will be described in connection with the accompanying drawings in which Figure 1 is a view, partially in elevation and partially in section, of a portion of an engine fly wheel with my invention applied thereto. Fig. 2 is a diagrammatic view of circuits and apparatus embodying my invention.

A fly wheel 1, only a portion of which is shown, and which may be operatively connected to the shaft of an internal combustion engine, is provided with gear teeth 2. An electric motor 3 has an armature 4 which is arranged for longitudinal movement in bearings 5. A spring 6, which is interposed between one end of the armature shaft 7 and a collar member 8 that is rotatably mounted in alignment therewith, tends to maintain the armature in a displaced position relatively to the field magnet frame 3. The commutator cylinder 9 is of such length that it is always in engagement with coacting brushes 10 that are secured to the motor frame.

The opposite end of the armature shaft 7 comprises a screw-threaded portion 11 upon which is mounted a pinion 12 having corresponding screw threads. The armature shaft 7 is further provided with a collar member 13 at the inner end of the screw-threaded portion and a buffer spring 14 that is secured to the collar member 13 for receiving the impact of the pinion 12 as it is shifted longitudinally into mesh with the gear teeth 2.

To start the motor, a push button switch 15, which may be located at any suitable point within convenient reach of the operator, is actuated to complete a circuit comprising the coil 16 of a relay switch 17 and a storage battery 18. The switch 17 then closes the motor circuit which comprises the series field winding 19 and the armature winding 20. The field-magnet poles are en-

ergized to exert a strong magnetic pull upon the armature whereby it is shifted toward its central position.

The pinion 12 is thereby shifted nearly 5 into engagement with the gear teeth 2 before the armature has attained a high rate of speed. The rapidly accelerating armature shaft 7, which rotates in a counter clockwise direction, as viewed from the right, Fig. 1, 10 operates through the screw-threaded portion 11 to shift the pinion 12 completely into mesh with the gear teeth 2. Because of the relatively high inertia of the pinion 12 and the low pitch of the screw-threads on the 15 portion 11, the pinion 12 does not rotate with the shaft 7. The pinion is accordingly shifted longitudinally of the shaft into engagement with the gear teeth of the fly-wheel. If the coacting gear teeth do not 20 register properly, the pinion 12 may rotate temporarily with the shaft 7 in order that they may assume their proper relative positions. The motor then operates to crank the engine through the connections above 25 described.

When the engine starts under its own power, the pinion 12 will be rotated by the fly wheel 1 at a higher rate of speed than it is driven by the motor. The pinion is 30 thus caused to overrun the shaft 7 and is shifted to the right by the screw threads until it is out of engagement with the gear teeth 2 to disconnect the motor from the engine.

35 The operator may release the push button 15 at any time after the engine has started. If the operator fails to open the motor circuit at the proper time, no harm can result even if the screw-threads fail to 40 act. The increasing counter-electromotive force of the motor causes a corresponding decrease in the current traversing the motor circuit. The spring 6 operates, when the longitudinal pull has fallen to a pre- 45 determined value, to return the armature to its illustrated position. This action may occur before the pinion has been shifted by the screw threads. Thus, there are provided two independent means for automatically 50 shifting the pinion 12 out of mesh with the fly wheel gear.

I claim as my invention:

55 1. In a starting mechanism, the combination with a pair of coacting gear wheels, and a screw-threaded shaft for supporting one of said gear wheels, of means for simultaneously rotating said shaft and shifting it longitudinally.

2. In a starting mechanism, the combina-

tion with a pair of coacting gear wheels, 60 and a screw-threaded shaft for supporting one of said gear wheels, of electro-responsive means for simultaneously rotating said shaft and shifting it longitudinally.

3. In a starting mechanism, the combination with a pair of coacting gear wheels, and a screw-threaded shaft for supporting one of said gear wheels, of a motor for simultaneously rotating said shaft and shifting it longitudinally. 70

4. In a starting mechanism, the combination with a pair of coacting gear wheels, of means for shifting one of said gear wheels, into and out of mesh with the other, said means comprising a screw-threaded 75 shaft and means for shifting the shaft longitudinally and rotating it relatively to said pinion.

5. In a starting mechanism, the combination with a pair of coacting gear wheels, of 80 means for shifting one of said gear wheels into and out of mesh with the other, said means comprising a screw-threaded shaft and electro-responsive means for shifting the shaft longitudinally and rotating it 85 relatively to said pinion.

6. In a starting mechanism, the combination with a pair of coacting gear wheels, of means for shifting one of said gear wheels into and out of mesh with the other, said 90 means comprising a screw-threaded shaft, and a motor for shifting the shaft longitudinally and rotating it relatively to said pinion.

7. In a starting mechanism, the combination with a pair of coacting gear wheels, of means for shifting one of said gear wheels into and out of mesh with the other, said means comprising a screw-threaded shaft and a motor having a normally displaced 100 armature for shifting the shaft longitudinally and rotating it relatively to said pinion. 95

8. In a starting mechanism, the combination with a pair of coacting gear wheels, of 105 means for controlling their relative positions, said means comprising an electric motor having a longitudinally shiftable armature, and an armature shaft having a portion inclined relatively to its axis for co- 110 acting with one of said gear wheels.

In testimony whereof, I have hereunto subscribed my name this 23rd day of Dec., 1914.

CHARLES E. WILSON.
